UNITED STATES PATENT OFFICE.

HOWARD H. BRISTOL, OF NAUGATUCK, CONNECTICUT, ASSIGNOR TO THE BRISTOL COMPANY, OF WATERBURY, CONNECTICUT, A CORPORATION OF CONNECTICUT.

PORTABLE ELECTRICAL TRANSMITTER UNIT FOR PHONOGRAHS.

Application filed May 1, 1926. Serial No. 105,993.

The invention relates to apparatus for reproducing sound, more particularly to apparatus of the phonographic or talking machine type utilizing a rotating record member and a stylus adapted to move in the grooves thereof. It has for its object the provision of electrical transmitter apparatus of the microphone type and carrying the said stylus, more especially in the nature 5 of a self-contained unit which may readily be associated with the record rotating member of a phonograph and having a movable arm carrying the transmitter member which is actuated by said stylus. A further object 10 of the invention consists in means embodied in said unit whereby, when the transmitter is not in use, it may be suitably supported and the actuating current for transmitting the sound vibration at the same time automatically cut off.

A still further object of the invention resides in a portable unit of the aforesaid type which is compact and so constructed that it will be stable without permanent 25 attachment and will form a substantial support for the movable transmitter carrying arm. This obviates the necessity of providing attaching means which would mar to a greater or less degree the phonograph 30 with which it is desired to associate the unit.

The nature of the invention, however, will best be understood when described in connection with the accompanying drawings, in which—

35 Fig. 1 is a fragmentary side elevation of a phonograph turntable and the associated unit, together with a loud speaker device operated thereby.

40 Fig. 2 is a side elevation of the unit with portions broken away; and Fig. 3 is a fragmentary front elevation of the unit with transmitter arm cut off.

45 Fig. 4 is a fragmentary plan of a turntable and record and a horizontal section thru the unit associated therewith, and illustrates the transmitter arm in operative position for playing the record.

Fig. 5 is a fragmentary plan view of the unit with portion of top broken away and

with transmitter arm in its inoperative position.

Referring to the drawings, 10 designates a supporting table or base upon which is mounted a phonograph turntable 11 as a suitable means for rotating a phonographic record 12 and operated in any suitable and well-known manner for imparting the proper speed thereto, which record may be of the usual disk type shown. With this turntable and record is adapted to be associated the 55 novel and portable transmitter unit hereinafter more fully described and contained with a casing 13 mounted upon a weighted base 14. The under face of the base may be provided with a suitable covering as of 60 felt to insure against scratching or otherwise marring of the upper surface of the support 10. Said base is provided also with a plurality of sockets 15 for plugging in, for example, the battery 16 for operating 65 the transmitter and a loud speaker device or the like 17. It is understood, of course, that usual amplifying means (not shown) may also be included, if desired, in the circuit to the speaker device 17.

70 In the casing 13 is suitably mounted to swing in a horizontal plane and a vertical plane an arm 20 carrying at its outer end an electrical transmitter 21 of the microphone type. The latter is designed to carry 75 a stylus 22 adapted to fit in the grooves of the record 12 to actuate thereby the diaphragm of the microphone in manner well understood to produce variations in the electrical current, but forms no particular 80 part of the present invention.

85 The invention relates more particularly to the provision of the self-contained portable unit comprising the arm 20 with microphone 21 attached thereto, the base 14 and casing 13 containing mechanism hereinafter described. For example, the casing 13 will contain a suitable transformer 23, condenser 24 and potentiometer 25, the latter having a shaft 26 projecting thru the top of the casing with knob 27 thereon for conveniently manipulating same to vary the resistance of the outgoing circuit to the speaker device,

the volume of reproduced sound thereof being accordingly varied thereby. A substantial weight 28 is also provided in the bottom of the casing to prevent overbalancing of 5 the same by the arm 20 and attached microphone 21 and assures a satisfactory support therefor.

In order for the stylus 22 to readily follow the grooves of the record 12, it will be 10 understood that arm 20 must have a movement both in a horizontal plane and in a vertical plane; and to this end, said arm may be carried by a sleeve 30 fitting over a stud 31 projecting upwardly from the bottom 15 of the casing, said sleeve being vertically positioned by a pin or screw 32 fitting into a groove 33 of the stud. The upper end of sleeve 30, moreover, is bifurcated and the inner end 34 of arm 20 is pivotally connected thereto. The casing wall, furthermore, is cut away as at 35 to permit arm 20 to swing over the desired arc in a horizontal plane. There extends also radially from 20 said casing, as by being fixedly attached thereto in any suitable manner, a bracket member 36 in the plane of horizontal movement of the arm 20 and having a curved arm 37 extending laterally from its end toward arm 20, the same being adapted to 25 receive the latter when it is at one of its extreme positions, to wit—just in advance of its starting position. When thus resting upon arm 37, said arm 20 is not intended to function nor the transmitter carried 30 thereby; and, accordingly, provision is made for automatically cutting off the current to the said transmitter lead thereto thru conductors 38. One of these conductors is, therefore, to be opened when the arm 20 is 35 in its inactive position as indicated in Fig. 5 of the drawings; and to this end, there bears upon the periphery of sleeve 30 a brush member 40, whereby when the sleeve is rotated contact will be maintained and 40 the microphone transmitter allowed to function. However, when sleeve 30 has moved to a position in which the arm 20 is substantially over the arm 37 of the bracket 36 so that it may rest thereon, an insulation 45 button or projection 41 also movable with said sleeve engages with the brush 40 to lift same from making contact with the sleeve 30 and thus opens the circuit at this point. There is little danger, therefore, of 50 leaving the apparatus when not in use in a position which would cause current to continue to be consumed and to the detriment of the microphone transmitter. As soon as arm 20 is again moved outwardly, the insulating 55 projection 41 moving with sleeve 30 permits brush 40 to again make contact with the said sleeve, rendering the transmitter alive and ready for reproducing sound from the record 12.

I claim:—

1. An electrical transmitter unit for phonographs, comprising a casing, an arm extending therefrom and swingably mounted therein to oscillate in a horizontal plane and also in a vertical plane, a microphone carried at the outer end of said arm and conductors therefrom extending into the casing for external connection, a stationary supporting bracket extending outwardly from the casing substantially in the plane of horizontal movement of the microphone carrying arm and adapted to support the latter, and means moving with said microphone carrying arm to cut off the actuating current to its microphone transmitter when the said arm rests on the said stationary bracket. 70

2. An electrical transmitter unit for phonographs, comprising a casing, an arm extending therefrom and swingably mounted therein to oscillate in a horizontal plane and also in a vertical plane, a microphone carried at the outer end of said arm and conductors therefrom extending into the casing for external connection, a stationary supporting bracket extending outwardly from the casing substantially in the plane of horizontal movement of the microphone carrying arm and adapted to support the latter, means moving with said microphone carrying arm to cut off the actuating current to its microphone transmitter when the said arm rests on the said stationary bracket, 80 and a weight in the bottom of said casing to overbalance the moment of the microphone arm and microphone transmitter. 85

3. An electrical transmitter unit for phonographs, comprising a casing, a vertically disposed sleeve mounted for oscillation therein, an arm extending from the casing and movable with the sleeve in a horizontal plane and also in a vertical plane, a stationary supporting bracket extending outwardly from the casing substantially in the plane of horizontal movement of the said movable arm, a microphone carried at the outer end of said movable arm, and conductors therefrom to said casing for external connection, a contact brush bearing against said vertically disposed sleeve and included in circuit with one of the said conductors, an insulation projection on said sleeve, movable therewith in the plane of said brush and adapted to engage and lift the brush off the sleeve to interrupt the circuit to the microphone transmitter when the carrying arm of the latter is turned to a position to bring it to rest upon the said stationary bracket. 100

4. An electrical transmitter unit for phonographs, comprising a casing, an arm extending therefrom and swingably mounted therein to oscillate in a horizontal plane and also in a vertical plane, a microphone 110

carried at the outer end of said arm and conductors therefrom extending into the casing for external connection, a stationary supporting bracket extending outwardly 5 from the casing substantially in the plane of horizontal movement of the microphone carrying arm and having a laterally extending arm for receiving and supporting said

microphone carrying arm against motion in the vertical plane, and means moving 10 with said microphone carrying arm to cut off the actuating current to its microphone transmitter when the said arm rests on the said laterally extending arm.

In testimony whereof I affix my signature.
HOWARD H. BRISTOL.
